UNITED STATES PATENT OFFICE.

EZRA B. MEAD, OF OTTUMWA, IOWA, ASSIGNOR TO OTTUMWA IRON WORKS, OF OTTUMWA, IOWA, A CORPORATION OF IOWA.

EMERGENCY-BRAKE CONTROL.

Application filed July 30, 1921. Serial No. 488,561.

To all whom it may concern:

Be it known that I, EZRA B. MEAD, a citizen of the United States, residing in Ottumwa, in the county of Wapello and State 5 of Iowa, have invented a new and useful Improvement in Emergency-Brake Controls, of which the following is a specification.

This invention relates in general to hoisting apparatus and has more particular reference to the brake control provided for use in drum hoists which are employed for moving trains of cars on a slope, though it should be observed that it is not limited to 10 any particular type of hoisting device and may be of general application in hoisting and elevating machinery.

In hoists such as are employed in the mines and elsewhere it is usually the custom to provide for the emergency application of the brake under certain predetermined conditions, as for example, when the power fails, excessive speed is attained, and the like. These controls work admirably when the train of cars is moving 25 downward but difficulty has been encountered in controlling the application of the brake in the up movement of the train. The reason for this is readily apparent since apparatus of this character is usually actuated by the winding and unwinding of a cable upon a drum located either at the top of the slope or elsewhere and brake application is made to the drum or shaft upon which the 30 drum is mounted. If the drum be slowed at a speed faster than the gravity retardation of the upwardly moving train the rope slackens and when the train is finally brought to rest it may then have a free fall 35 or free run taking up the slack thus provided. This action, of course, has a tendency and has been known to break the cable permitting the train to violently descend.

It is a principal object of my invention to provide means for controlling the emergency application of the brake so that the drum will not be slowed in excess of the gravity retardation of the upwardly moving 45 load. In the present instance the apparatus embodying the invention is adapted, if desired, to place a light braking action by the hoist brake during the remaining up movement or preferably to delay the action of 50 the hoist brake until the hoist is brought to

rest by gravity and then immediately apply it before the hoist has opportunity to move downwardly an appreciable distance.

Another important object of my invention is the provision of apparatus of this 60 character, which need not interfere in any particular with the manual control of the hoist brake and which need not require reconstruction of the brake control, the emergency mechanism or the devices controlling 65 it.

Another highly important object of my invention is the provision of an apparatus accomplishing the aforesaid general purpose, which in service will have no moving 70 parts except when actually in operation and which on this and other accounts will not require frequent repair, replacement or readjustment.

Numerous other objects and advantages of 75 the invention will be apparent as it is better understood from the following description, which, taken in connection with the accompanying drawings, discloses a preferred embodiment thereof.

Referring to the drawings,

Fig. 1 is a side elevation of the controller for operation of the brake control mechanism of the character described;

Fig. 2 is a side elevation of the brake deferring or delaying portion of the apparatus;

Fig. 3 is a view looking from the right in Fig. 2;

Fig. 4 is a section taken substantially on 90 the line 4—4 of Fig. 2; and

Fig. 5 is a section taken substantially on the line 5—5 of Fig. 2.

For the purpose of illustrating my invention I have shown on the drawing in Fig. 1 a side view of a brake controller mechanism in which is provided an arrangement for both manual and emergency hoist brake application. The brake itself is not shown on the drawing since it may be of any well-known or preferred construction and is fluid actuated, compressed air, oil or water being employed. Brakes of this character are usually and desirably applied through the agency of powerful weights or springs, 100 the brake being released by overcoming the pressure exerted by the weights or the springs through some fluid agency.

Referring to Fig. 1 reference character 11 indicates a valve casing in which is mount- 110

ed the necessary valve parts to cause fluid under brake releasing pressure to pass to the brake cylinder in the known fashion. This valve is preferably of the character of that described in U. S. Letters Patent No. 1,373,196 issued to the Ottumwa Iron Works as my assignee on March 29, 1921. The brake control shown in Fig. 1 in many respects is like that of this patent. It comprises an operating shaft 12 mounted in a suitable bearing construction 13 and carrying a loosely mounted brake lever 14 of bell crank construction. The valve control arm 15 of this lever 14 is angled at 16 and again at 17. The valve casing is supported in supports 18 from the bearing construction 13 and its valve stem 19 is attached to a plate 21 in turn attached at 22 to a floating lever 23. This lever extends at one end (the right) beneath the arm 15 of the manually controlled lever 14 and is attached at its other end at 24 to a lever 25 keyed on the shaft 12 at 26. The lever 25 engages under a latch 27 of an emergency control, this latch being mounted in the bearing 28 and having a weight 29 pulling it over into engaging position.

The pressure of the fluid in the brake control system is applied beneath the valve as is indicated in my prior patent above-mentioned, this pressure when conditions permit tending to raise the valve and permit release of the brake applying devices at the brake.

A counter weight 31 is pivoted upon a bar 32 connected by links 33 with the plate 21, 35 this counter weight, however, being less than the pressure within the valve. An arm 34 is also keyed upon the shaft 12 and from this arm a weight 35 is suspended by a rod 36. Set screws 37 and 38 are provided in the arm 15 of the manually controlled lever to produce operation of the float lever 23. When it is desired to apply the brakes the lever is moved in a counter-clockwise direction, viewing the figure, and the valve 40 opened to exhaust from the brake operating cylinder and this pressure may be restored to release the brakes by movement in the opposite direction. When emergency conditions, requiring application of brake, occur 45 the trip 27 is moved over electromagnetically or otherwise permitting release of the lever 25, thus freeing the valve from restraining action and permitting it to rise. In this connection the weight 35 is opposed 50 to the weight 31 and emergency brake application may result. So much of the apparatus as has just been described is of the general type shown in my prior patent above referred to and more particular showing and 55 description is not, therefore, thought necessary.

In order to prevent movement of the brakes in emergency action during ascension I provide a device or apparatus which will 60 now be described and it may be considered

as a separate attachment or as a part of the general brake control. Referring to Fig. 2, reference character 51 indicates the drum shaft or similar part moving in accordance with the drum either at like or at proportional speed. This shaft is mounted in suitable bearing at 52. In the present instance I arrange the device about the shaft providing an embracing band or member 53 very much like a band brake. This band at the lower end is attached at 54 to a member 55 which is connected by a link 56 with a pin 57 in an upright link 58. The other end of the band is pivoted at 59 in a lever 61 pivoted at one end at 57 in the link 58 and at the other at 62 to the upper end of a rod 63. The link 58 is pivoted respectively at 64 and 65 to links 66 and 67, these links being pivoted in turn at 68 and 69 in the main frame of the machine and preferably vertically beneath the center of the shaft 51. The link 67 is provided at its opposite end with a weight 71 and has a downwardly extending bracket construction 72 in which is pivoted the tail 73 of a second weight 74. 70 The tail 73 has a stop 75 for engagement with the other side of the link 67 and the weight 74 has a stop 76 adapted for engagement with the pin 77 in the frame, the purpose of which will be presently more fully described.

The rod 63 is connected at 78 with one arm 79 of a bell crank lever pivoted at 81 to the frame,—the other arm 82 of this bell crank is connected at 83 with a link on rod 84 engaged at 80 with an arm 85 also connected on the operating shaft 12 of the brake control mechanism. The arm 85 is keyed on the operating shaft so that it moves with any movement of the lever 25.

When the trip is released during the up-movement of the train, the trip lever 25 tends to move up tightening the band 53. This causes the band to tend to rotate with the drum shaft 51. This results in a downward swinging movement of the weight 71 and an upward swinging movement of the weight 74 about the stop 77, these two weights soon coming to rest by engagement with each other and permitting the shaft 51 to slip. This movement permits a slight compensation for the movement of the trip lever 25 and no emergency application of the brake has resulted. When the shaft 51 comes to rest it immediately starts in the reverse direction under the gravity action of the train. This causes the band 53, which is still tightly about the shaft, to tend to move in the opposite direction and the two weights may be swung about the pivot points 69, the link 58 thus moved downwardly and emergency brake application results.

Attention is directed to the angularity of the bell crank consisting of the arms 79 and 82 and also its angular relation with respect 130

to the rods 63 and 84. This arrangement produces minimum motion of the trip lever 25 for a given movement of the little lever 61.

5 The band 53 in the normal running of the apparatus is out of contact with the shaft, the parts being overbalanced by the weights 71 and 74. A support 86 is provided for the band. It is to be noted that during this normal operation, none of the brake parts are 10 in motion or in contact with parts which are in motion, so that no opportunity for wear at such times is provided.

The parts may be so set and arranged that 15 the little lever 61 will not wholly compensate for the tripping movement with slight braking action resulting on the up-stroke. All that is required in this respect is a sufficient movement of the parts to permit the 20 valve to open slightly as will be readily understood.

The shaft 51, when the drum is hoisting, rotates in counter-clockwise direction, as indicated by the arrow in Fig. 2. As previously stated, the band 53 is not affected by 25 normal rotation of said shaft and is only brought into contact therewith when the trip lever 25 is actuated. In this event, it moves with the shaft until stopped by the 30 action of the weights 71 and 74, the shaft then slipping within the band until brought to rest. Upon reversal of direction of rotation of the shaft 51 and band 53, the latter is loosened and the lever 25 may be moved 35 sufficiently to permit the emergency brake to be applied.

It is thought that the invention and many 40 of its attendant advantages will be understood from the foregoing description, and it will be apparent that various changes may be made in the form, construction and arrangement of the parts without departing 45 from the spirit and scope of the invention or sacrificing all of its material advantages the form hereinbefore described being merely a preferred embodiment thereof.

I claim:

1. In a hoisting apparatus including a 50 hoist mechanism and a brake therefor, the combination of an emergency control for said brake, and means for preventing braking action under the emergency control in advance of gravity retardation while the hoist is lifting, said means comprising a member rotatable with the hoist and means actuated by contact with said member for delaying the application of the brakes.

2. In a hoisting apparatus including a 60 hoist mechanism and a brake therefor, the combination of an emergency control for said brake, and means for delaying braking action under the action of said emergency control while the hoist is lifting, said means comprising a member rotatable with the 65 hoist and means actuated by contact with

said member for delaying the application of the brakes.

3. In a hoisting apparatus, provided with a hoist drum and a brake, the combination of a member moving in accordance with said 70 drum, means for applying said brake, an emergency release for said means, and a device engaging said member to prevent actuation of the brake while the member is moving in accordance with the up movement of 75 the drum.

4. In a hoisting apparatus, provided with a hoist drum and a brake, the combination of a member moving in accordance with said 80 drum, means for applying said brake, an emergency release for said means, and a device moved into engagement with said member by the initial action of said release for preventing brake application during the up 85 movement of the drum.

5. In a hoisting apparatus, provided with a hoist drum and a brake, the combination of a member moving in accordance with said 90 drum, means for applying said brake, an emergency release for said means, and a device movable into engagement with and actuated by said member to facilitate the action of said release during the down movement of the drum.

6. In a hoisting apparatus, provided with 95 a hoist drum and a brake, the combination of a member moving in accordance with said drum, means for applying said brake, an emergency release for said means, and a device movable on the operation of said 100 release into engagement with said member during the up movement of the drum to prevent action of said brake applying means during the up movement of the drum and permitting release of said brake applying means during the down movement of the 105 drum.

7. In a hoisting apparatus, provided with 110 a hoist drum and a brake, the combination of a member moving in accordance with said drum, means for applying said brake, an emergency release for said means, and a device movable on the operation of said release into engagement with said member during the up movement of the drum to prevent action of said brake applying means during the up movement of the drum, and permitting application of said brake applying means as soon as the drum starts its 115 downward movement.

8. In a hoisting apparatus, provided with 120 a hoist drum and a brake, the combination of a member moving in accordance with said drum, means for applying said brake, an emergency release for said means, and a device embracing said member and adapted to be tightened thereabout by the initial 125 action of said release for controlling its releasing action to prevent brake application during the up movement.

9. In a hoisting apparatus, provided with a hoist drum and a brake, the combination of a member moving in accordance with said drum, means for applying said brake, an emergency release for said means, and a device embracing said member and adapted to be tightened thereabout by the initial action of said release, said device being movable against the releasing action in one direction to prevent brake application and with the releasing action in the opposite direction of drum movement to permit brake application.
10. In a hoisting apparatus, provided with a hoist drum and a brake, the combination of a member moving in accordance with said drum, means for applying said brake, an emergency release for said means, and a device embracing said member and adapted to be tightened thereabout by the initial action of said release, said device having a slipping engagement with said member during the up movement of the drum to prevent brake application.
11. In a hoisting apparatus, provided with a hoist drum and a brake, the combination of a member moving in accordance with said drum, means for applying said brake, an emergency release for said means, and a device embracing said member and adapted to be tightened thereabout by the initial action of said release, said device being held against substantial movement with said member in the up movement of the drum to prevent brake application.
12. In a hoisting apparatus, a drum shaft, means for applying a brake to said drum shaft, means for releasing said brake applying means; an emergency control for said releasing means, and a device embracing said drum shaft, said device being movable into engagement with said shaft in the initial movement of the emergency control, rotation of said shaft in the up movement of the drum delaying the emergency control action.
13. In a hoisting apparatus, a drum shaft, means for applying a brake to said drum shaft, means for releasing said brake applying means, an emergency control for said releasing means, and a device embracing said drum shaft, said device being movable into engagement with said shaft in the initial movement of the emergency control, rotation of said shaft in the up movement of the drum delaying the emergency control action until the down movement of the drum occurs.
14. In a hoisting apparatus, a drum shaft, means for applying a brake to said drum shaft, means for releasing said brake applying means, an emergency control for said releasing means, and a device embracing said drum shaft, said emergency control including a trip releasing said control under certain predetermined conditions, and said device embracing the drum shaft being moved into engagement therewith on release of the trip for preventing actuation of said emergency control during the up movement of the drum and until it starts its down movement.

EZRA B. MEAD.
